2192

UNITED STATES PATENT OFFICE.

CATHERINE SHEILS, OF NEW YORK, N. Y., ASSIGNOR TO THE BUTTERICK PUBLISHING COMPANY, (LIMITED,) OF SAME PLACE.

DESIGN FOR A GIRL'S DRESS.

SPECIFICATION forming part of Design No. 18,483, dated July 24, 1888.

Application filed June 15, 1888. Serial No. 277,272. Term of patent 3½ years.

To all whom it may concern:

Be it known that I, CATHERINE SHEILS, of the city, county, and State of New York, have invented and produced a new and original 5 Design for a Pattern of a Girl's Dress; and I do hereby declare that the engraved prints accompanying this specification convey to any one accustomed to using paper patterns a clear understanding of how a garment made up by 10 to the pattern will appear.

The design shows a high-necked body that exhibits a puff yoke at the top; a low-necked front displaying a Shirred center front and a pointed lower edge; a low-necked back exhibiting plaits down its center, a standing collar,

and coat-sleeves having double puffs reaching below the elbows; a full skirt that displays box-plaits in front and tucks and a fullness at the side and back, and sash-ties extending from the under-arm seams and forming a longer 20 bow at the back.

What I claim as my invention, and desire to secure by Letters Patent, is—

The design for a girl's dress, as shown in the engraved prints accompanying this specification. 25

CATHERINE SHEILS.
